(57) **CLAIM**

The ornamental design for a monitor stand, as shown and described.

DESCRIPTION

FIG. 1 is a front elevation view of a monitor stand;
FIG. 2 is a rear elevation view thereof;
FIG. 3 is a left side elevation view thereof;
FIG. 4 is a right side elevation view thereof;
FIG. 5 is a top plan view thereof;
FIG. 6 is a bottom plan view thereof; and,
FIG. 7 is a front, top and right side perspective view thereof.
The broken lines shown in FIGS. 1-4 and 6-7 illustrate portions of the monitor stand that form no part of the claimed design.

1 Claim, 7 Drawing Sheets
